UNITED STATES PATENT OFFICE.

JUAN BERNARDO ORTHOLAN, OF BUENOS AIRES, ARGENTINA.

TWO-CYCLE ROTARY-CYLINDER ENGINE.

1,147,540.

Specification of Letters Patent. Patented July 20, 1915.

Application filed May 13, 1915. Serial No. 27,820.

To all whom it may concern:

Be it known that I, JUAN BERNARDO ORTHOLAN, a citizen of Argentina, residing at No. 671 Calle Maipú, Buenos Aires, Argentina, have invented an Improvement in Two-Cycle Rotary-Cylinder Engines, of which the following is a specification.

The present invention relates to certain novel and useful improvements in the construction of rotary cylinder engines, and has for its object to provide means by which each one of the elements or cylinders constituting it, may work in two cycles, instead of in four, as it is the common principle under which the engines of the abovesaid type work.

My present invention has in view to increase the efficiency of the said type of engines up to a degree that has not been reached heretofore and taking into consideration the weight and the energy developed, the efficiency is about twice that of the four cycle system.

The essential feature of my present invention consists in utilizing the centrifugal force as main agent for the discharge of the combustion gases and for the admission of the explosive gas or mixture in a regular and perfect form during the cycle of each one of the cylinders, by which means a maximum of regularity and efficiency in the working is obtained.

Although improved in certain details, the general construction of the engine does not differ from that of the ordinary engines and it is obvious that it may be altered, and that the number of cylinders may be increased or diminished, without in the least affecting the validity of my present invention.

The discharge step, the initial fraction of the same excepted, is effected simultaneously with the admission, in such a form, that, though inverted, it is similar to the principle under which the usual two cycle engines of the fixed type operate. The only difference lies in the fact that in these latter the admission of the carbureting gas in the cylinders is effected under pressure, and though in an imperfect manner, it determines the discharge of the burned gases, whereas, according to the principle of the present invention, this object is obtained precisely in an opposite manner. In fact, the discharge of the burned gases is effected by the centrifugal force and this forced discharge and even the tendency to such a discharge deter-

mine the admission in the cylinders of the carbureting gases.

A practical embodiment of the invention is represented in the accompanying drawing forming a part of this specification and in which the figure is a sectional elevation of the improvement.

In the drawing 1 is a crank case mounted on steel balls 2, which rotates on a standard and tubular axle 3, forming part of the crank-axle 4. The cylinders 5, provided with ordinary radiators, have two series of holes 6' and 14. The plungers 10 move in the cylinders, actuating the connecting rods 11, which have their ends fixed on the head 12, secured to the crank-axle 4.

Tubes 8 lead from the crank case to the admission holes 6' which comprise a semi-circle of the cylinder. To complete this semi-circle, the holes 14 have been made which communicate unitedly with the exhaust tube 13. The tubes 13 extend outward approximately parallel with the cylinders and beyond the ends of the same. The tubes 13 not only serve as exhaust but in addition thereto serve to draw in the explosive mixture from the crank case to the cylinders. The holes 14 which start from the same level as the holes 6', go somewhat higher up than the others, so that the displacement of the plunger uncovers a fraction of the first named, permitting the exhaust only before uncovering also the second ones so as to realize the exhaust and the admission simultaneously.

At the surface of the plungers a semicircular baffle 15 has been placed before the holes 6' which produces the precipitation of the combustible gas against the head of the cylinder at the same time as the used gases are dislodged from the same. The plungers are of sufficient length to cover in their furthest advance the whole of the holes 16 and 6'. The gas is introduced into the crank case by aspiration or by means of a mechanical carburetor, through the tube 3 serving as an axle for the engine. In this way the accumulation of gas in the crank case is maintained to supply the cylinders. It will be readily understood that the arc of circle run by the cylinders in their rotary movement from the points where the pistons uncover the openings to where they close the said openings is so ample, it will be possible to fully discharge the burned gases and to have them substituted by the carbureting gases,

on ground of the greater specific weight of these latter and also of the circulation originated by the centrifugal force.

Having now fully described and ascertained the nature of my said invention and in what manner the same is to be performed, I declare that what I claim, is:

A rotary internal combustion engine of the non-compression type, comprising a revoluble crank case, a plurality of cylinders mounted on the crank case and having their inner ends opening into the same, pistons in the cylinders, a crank shaft in the crank case, piston rods connecting the pistons with

the crank shaft, an admission tube connecting the crank case with the inner end of each cylinder, and an exhaust tube leading from each cylinder on the side opposite the admission tube, and extending approximately parallel with the cylinder and approximately 15 to the outer end thereof, whereby the said exhaust tube serves as an additional means for drawing in the explosive mixture to the cylinder. 20

JUAN BERNARDO ORTHOLAN.
